(57) **CLAIM**

The ornamental design for a toner loading bottle, as shown and described.

DESCRIPTION

The ornamental design disclosed in this application is for a toner loading bottle for use with electrostatographic office equipment, to which the following is the specification, reference being made to the accompanying drawings, forming a part thereof.

FIG. 1 is a perspective view of the toner bottle, showing the bottom surface and one side surface of our new design; FIG. 2 is a side view of an unfaceted side surface thereof; FIG. 3 is a side view of the toner bottle rotated 90° from the surface of FIG. 2, showing both faceted and unfaceted surfaces;

FIG. 4 is a side view of the toner bottle rotated 180° from the view of FIG. 2, showing faceted surfaces;

FIG. 5 is a side view of the toner bottle rotated 270° from the view of FIG. 2, showing both faceted and unfaceted surfaces;

FIG. 6 is a plan view of the toner bottle, showing the bottom surface; and,

FIG. 7 is a plan view of the toner bottle, showing the top surface.
